(57) **CLAIM**

The ornamental design for a toilet lifter, as shown and described.

DESCRIPTION

FIG. 1 is a perspective illustration of the toilet lifter in a preferred position;

FIG. 2 is a closer perspective view of the toilet lifter;

FIG. 3 is a frontal view of the toilet lifter;

FIG. 4 is a top plan view of the toilet lifter; and,

FIG. 5 is a side profile thereof.

The broken lines form no part of the claimed design.
